UNITED STATES PATENT OFFICE.

HECTOR RABEZZANA, OF FLINT, MICHIGAN.

DESIGN FOR A CAN-TESTER.

58,684.

Specification for Design.

Patented Aug. 9, 1921.

Application filed April 28, 1921. Serial No. 465,229. Term of patent 14 years.

To all whom it may concern:

Be it known that I, HECTOR RABEZZANA, a citizen of the United States, residing at Flint, in the county of Genesee and State of Michigan, have invented a new, original, and ornamental Design for Can-Testers, of which the following is a specification, reference being had to the accompanying

drawing, forming part thereof and in which is shown a perspective view of the device.

I claim:

The ornamental design for a can tester, as shown.

HECTOR RABEZZANA.
